UNITED STATES PATENT OFFICE.

EARL B. DARLING, OF KANSAS CITY, MISSOURI.

DRIER.

Application filed May 1, 1925. Serial No. 27,201.

This invention relates to driers and particularly to curtain driers.

The primary object of the invention is to provide a drier having an article carrier so constructed that the article to be dried may be conveniently attached to and removed from the carrier without danger of injury to the operator. It is also the purpose of the invention to provide a drier with the carrier upon which articles may be placed or removed while others are drying.

The invention also contemplates the provision of means for conveniently and efficiently handling curtains, the illustrated embodiment of the invention being shown as a curtain drier and to this end the invention consists in certain novel parts and combinations of parts, all of which will be specifically described hereinafter, reference being had to the accompanying drawings, in which

Fig. 1 is a perspective view of a drier constructed in accordance with my invention.

Fig. 2 is a cross sectional view through the drier casing, the carrier being shown in end elevation and the heating coil being shown in section.

Fig. 3 is a perspective sectional view through the side bars of the adjustable frame.

Fig. 4 is a fragmentary plan view of one of the side bars showing the detent for holding the side bar in fixed position.

Fig. 5 is a perspective view of the stay brace for holding the curtain supporting bar from sagging, and

Fig. 6 is a cross sectional view through one of the bars of the curtain supporting frame.

The casing 1 of the drier consists of a substantially hollow rectangular structure having a cover 2 with a central opening 3 therein, the edge of the opening being bounded by an upstanding inwardly directed flange 4 which extends entirely around the four sides of the opening. In the bottom of the casing is shown a heating coil 5. The heating coil may be of any appropriate construction so it is considered unnecessary to specifically describe it.

Mounted in end bearings 6 and 7 in the ends of the casing is a longitudinally disposed shaft 8 carrying a rectangular frame having three sides 9, 10 and 11 connected to the shaft by the spider arms 12, 13 and 14. Each side is substantially the width of the opening 3 and each side carries a fabric supporting structure particularly adapted

for supporting curtains. Each frame is a counterpart of the frames carried by the other two faces of the triangular carrier so it will be necessary only to describe one of them.

Each frame consists of two fixed end bars 15 and 16, one (15) having a plurality of upstanding pins 17 adapted to project through the curtain fabric to hold it to the frame, the other (16) being a guide bar in the form of a Z-bar to support the ends of the adjustable side bars 18 and 19 which like the bar 15 are provided with upstanding pins 20 and 21 to pass through the curtain fabric to hold it on the frame. The lower ends of the bars 18 and 19 are supported by the flange 22 carried by the bar 15. Therefore the bars 18 and 19 may slide toward and away one from the other transversely across the carrier.

In order that the bars 18 and 19 may move in unison, I have provided two endless belts 23 and 24. The belt 23 passes around pulleys 25 and 26. The belt 24 passes around pulleys 27 and 28. The bar 18 is fastened to the belts 23 and 24 at 29 and 30. The bar 19 is fastened to the belts 23 and 24 at 31 and 32. Therefore if one bar is moved away from the longitudinal center, the belts will move the other bar a corresponding distance and vice versa. One of the bars is provided with a detent.

In Fig. 4 I have shown the bar 19 as carrying an elbow lever 33, one arm 34 of which is pivoted to the bar at 35. The other arm constitutes a grip or handle 36 whereby the elbow lever can be rocked about the pivot 35. The arm 34 of the elbow lever is connected to a spring actuated bolt 37 by a link 38 passing through guide 39 on the bar 19. The spring bolt is of ordinary construction, the bolt having a shoulder against which one end of a spring (not shown) bears, the other end bearing against the end of the barrel or sleeve 39. This spring bolt construction is well known so it is deemed unnecessary to show it in detail or specifically describe it.

The bolt 37 is adapted to engage in the teeth of the rack bar 40, the rack bar having a calibrated scale 40' to indicate the distance between the bars 18 and 19 so that the operator may adjust the side bars 18 and 19 for the proper width of curtain. By pressing on the handle 36, the bolt 37 may be withdrawn from engagement with

the teeth of the rack bar 40, then the bars 18 and 19 can be spread apart to stretch the curtain after the curtain is fastened to the bars 15, 18 and 19.

- 5 When the bars 18 and 19 are moved the proper distance apart, the operator will release the grip on the handle 36 and allow the bolt 37 to engage the teeth so the bars will be held in proper adjusted position.
- 10 On opposite sides of the frame are upstanding channel shaped walls 41, 42 having perforations 43 and 44 to receive a transverse rod 45 adjustable longitudinally of the frame. The rod 45 has two constricted ends 46 and 47. The openings 44 are the size of the constricted end 47. The openings 43 are the size of the greatest diameter of the rod 45. There is a supplemental locking bar 48 in the channel of the bar 41. It has 20 perforations 50 the size of the constricted end 46. The locking bar 48 is normally urged against the web of the channel bar 41 by a spring 52 on the stud 53 carried by the lug 54. Therefore in order to insert the 25 bar 45, the end 46 is passed through the perforations 43 and into the perforations 50, then the rod may be projected through the perforations 43 far enough to allow the 30 constricted end 47 to engage one of the openings 44.

Upon releasing pressure against the bar 48 the spring 52 will force the rod 45 longitudinally into the perforation 44 so that the parts assume the position shown in Fig. 3, then the rod 45 is held in proper position. The rod 45 is adjusted longitudinally of the frame to take care of curtains of different lengths, it being understood that the purpose of taking out the bar 45 is to 40 permit it to pass through the hem at the top of the curtain after the manner of a curtain pole, so really the rod 45 constitutes a curtain pole or rod for supporting the upper end of the curtain, the lower end being 45 fastened to the bar 15.

By adjusting the rod or pole 45 longitudinally of the frame, the curtain can be stretched to the desired amount and by adjusting the bars 18 and 19 transversely of 50 the frame, the crosswise stretch on the curtain can be effected. Obviously the longitudinal pull on the rod 45 would tend to sag it in the middle so in order to provide against sagging and in order to support the 55 curtain at its longitudinal center, I have provided a fixed longitudinal rod 55 carried by the ends of the frame. On this rod is a sliding stay brace. It consists of an open link member 56 (see Fig. 5) carried 60 by a plate 57 slideable on the rod 55.

The perforation 59 of the plate 57 is substantially equal to the diameter of the rod 55 so that a pull by the link 56 will cause the edge of the opening 59 to impinge upon the 65 rod 55 and thereby prevent sliding of the

plate. Therefore it will be observed that the stay brace can be adjusted longitudinally of the rod 55 so as to hold the middle part of the rod or pole 45 from sagging.

As above explained, each face of the triangular carrier, carries a counterpart of the structure shown at the top of the casing in Fig. 1, and inasmuch as it is desirable to hold the carrier rigid while the fabric is being attached to the frame presented to the operator or while the fabric is being detached, I have provided a detent or locking means comprising a vertically reciprocatory member 60 slideable in one end of the casing and normally urged upwardly by 70 spring 61 attached to the member and to the end of the casing. The member has an offset finger 62 which may abut against one of the faces 63, 64 or 65 of the bars 9, 10 and 11 as clearly seen in Fig. 1. The member may be moved out of engaging position by pressing down upon the end 66. It will be observed that the flange 4 fits relatively close to the carrier so that liability of the operator's hand being caught when the carrier is 75 rotated will be eliminated.

It will be observed that curtains on two sides of the carrier, for example 10 and 11 will be drying while the operator is removing or placing curtains upon the remaining 80 face exposed to view. Therefore the heat will be evaporating the moisture upon two sides at all times. Consequently the capacity of the machine will be increased over that where a single frame is used and that in 85 view of the construction shown, the operation of the machine can be practically continuous as it requires a very short time to dry the curtains in the casing as shown. By 90 continuous of course I do not mean that the frame is continuously operated because obviously it must be intermittent for the purpose of putting on the curtains and taking them off. It will also be apparent that the 95 curtains can be stretched in a convenient manner and expeditiously applied and detached from the carrier.

What I claim and desire to secure by Letters-Patent is:—

1. In a drier comprising a casing, a carrier, and means on the casing for supporting the carrier, curtain frames supported by the carrier, each frame comprising fixed end bars having offset shelves, adjustable side bars slideable on said shelves, a curtain rod 100 parallel with said fixed end bars, means for adjustably supporting the curtain rod, and means for bracing the intermediate portion of the curtain rod comprising a longitudinal rod and an adjustable stay brace on the longitudinal rod for engaging the curtain rod.

2. In a drier, a carrier, and curtain stretching means supported by the carrier including perforated rigid side bars, a supplemental 105 spring-pressed bar adjacent one of the

side bars and having perforations smaller than those of the adjacent side bar, a curtain rod having reduced ends oppositely receivable respectively in a side bar and in said supplemental spring-pressed bar, the bar adjacent said spring-pressed bar having enlarged perforations to receive the body por-

tion of said curtain rod for admission of the reduced end of said rod to the spring-pressed bar whereby the spring-pressed bar may ¹⁰ latch the curtain rod in position supported by said rigid side bars.

In testimony whereof I affix my signature,
EARL B. DARLING.
